AUTOMOBILE WINDOW OPERATING MEANS

Walter F. Shetzline, Los Angeles, Calif.

Application September 11, 1933, Serial No. 688,977

12 Claims. (Cl. 268—125)

My invention relates to improved means for operating the sliding glass panels of windows and the invention as herein disclosed is especially designed for use in conjunction with the 5 windows of motor vehicles, railway coaches and the like.

One of the principal objects of my invention is, to provide relatively simple, practical and efficient means for raising and lowering a window or sliding glass panel within its frame and 10 my improved construction utilizes as its motive force, the partial vacuum developed within the intake manifold of the internal combustion engine that is utilized for driving the motor vehicle and while this source of power for effecting movements of the window within its frame has heretofore been used, the present invention contemplates an improved arrangement for utilizing this source of power.

20 A further object of my invention is, to provide a vacuum actuated window operating mechanism and to combine therewith a brake or clutch construction for holding the window or sliding panel in both open and closed positions as well as in any adjusted intermediate 25 positions. The invention also contemplates an arrangement whereby the brake or clutch mechanism acts automatically and in synchronism with the window raising and lowering operation so that when it is desired to raise or lower the window the brake or clutch will be automatically released to permit the raising and lowering mechanism to function and when the window has been raised or lowered to the desired 30 point, the brake or clutch will automatically reengage a part of the operating mechanism to effectually clamp and hold the same against further movement.

35 A further object of the invention is, to provide simple and efficient means for guiding the window in its movements from one position to another and for snugly engaging the side edges of the window or sliding panel while at rest. In this connection it has heretofore been the general practice to provide felt runners for the 40 sliding glass panels of automobile windows and doors, but these felt runners have a tendency to absorb moisture and swell to such a degree during damp weather as to render it difficult 45 to open or close the window or panel.

50 My improved construction is especially designed to eliminate this difficulty and enables the window frame or glass panel to be firmly gripped and held in any position and at the same time permits the frame or panel to be

5 moved freely when the raising and lowering means is operated.

A further object of my invention is, to provide simple and efficient means for cushioning the window frame or panel from its sudden descent at the termination of its downward travel.

Further objects of my invention are, to provide means at the sides and top of the frame in which the sliding panel operates for effectively preventing vibration and consequent rattle of the sliding frame or panel, further, to provide a window operating mechanism that may be conveniently installed within a convex or curved door or vehicle body and further, to 15 provide a construction of the character referred to that utilizes an elliptical cylinder so that the required piston area may be obtained within the limited space between the sliding panel or door and the wall of the door or vehicle body. 20

25 A further object of my invention is, to provide a master valve that is incorporated within the distributing valve and which master valve is especially designed so as to retain the vacuum that prevails within the storage tank forming a part of the operating means.

30 A further object of the invention is to provide in the distributing valve, a plurality of hardened steel balls for the purpose of minimizing wear within said valve and enabling the latter to be easily operated at all times and further, to provide an improved form of check valve that will be highly effective in retaining the vacuum that prevails within the storage tank.

35 My present invention is an improvement upon the auto window operating means forming the subject matter of U. S. Letters Patent No. 1,919,671, issued to me August 25, 1933.

40 With the foregoing and other objects in view my invention consists in certain novel features of construction and arrangements of parts that will be hereinafter more fully described and claimed and illustrated in the accompanying drawings in which:

45 Fig. 1 is an elevational view of a motor vehicle having a sliding glass panel for closing the window opening in the upper portion of the door and showing my improved window operating means associated with said door and sliding panel.

50 Fig. 2 is a vertical section taken on the line 2—2 of Fig. 1.

55 Fig. 3 is an enlarged detail section taken on the line 3—3 of Fig. 1.

- Fig. 4 is an enlarged cross section taken on the line 4—4 of Fig. 1.
- Fig. 5 is a vertical section taken through the lower portion of the elliptic cylinder and showing the brake or clutch that is utilized for clamping a moving part of the operating mechanism to hold the same after movement.
- Fig. 6 is a horizontal section taken on the line 6—6 of Fig. 5.
- Fig. 7 is an enlarged vertical section taken on the line 7—7 of Fig. 1.
- Fig. 8 is an elevational view of the valve that is utilized for controlling the window operating mechanism.
- Fig. 9 is a vertical section taken through the center of the valve and showing the operating handle in its normal neutral position.
- Fig. 10 is a sectional view similar to Fig. 9 and showing the parts of the valve and the operating handle thereof in the positions that they assume when the mechanism is actuated to lower the window or sliding panel.
- Fig. 11 is a sectional view similar to Figs. 9 and 10 and showing the valve and operating handle in the positions assumed when the mechanism is actuated to raise the window.
- Referring by numerals to the accompanying drawings which illustrate a preferred embodiment of my invention, 10 designates the door of a motor vehicle, which door is provided in its upper portion with a window opening 11 and which opening is adapted to be closed by a sliding glass panel 12.
- The doors of practically all motor vehicles of the present construction have their lower portions curved inwardly as illustrated in Fig. 2, in order to conform with the contour of the vehicle body.
- Arranged in the door structure to the sides of the opening 11, are vertically disposed channels 13 and arranged in each channel adjacent to the sides thereof, are vertically disposed tubes 14, elliptical in cross section and composed of thin flexible metal that will yield readily under internal suction or partial vacuum. The upper ends of these tubes 14 are closed and the lower ends thereof are suitably connected, preferably by means of Y connections 15 to the outer ends of horizontally disposed tubes 16.
- Interposed between the collapsible tubes 14 and the side edges of the window or glass panel 12, are narrow channels 17 carrying strips 18 of felt or the like that directly engage the faces of panel 12 immediately adjacent to its side edges.
- Interposed between the side edges of panel 12 and the inner wall of channel 13 is a strip 19 of felt or analogous material. The strips 18 and 19 provide cushions for the edges of the glass panel and prevent vibration and rattle thereof.
- Arranged within the door 10, preferably at a point midway between its sides and immediately below the lower edge of the opening 11, is a vertically disposed cylinder 20 that is elliptical in cross section. This particular construction of cylinder is employed in order that the required piston area may be secured within the limited space between the inner wall of the door and the vertical path of travel of the sliding panel.
- Arranged for sliding movement within the elliptic cylinder 20 is a piston 21, to the underside of which is pivotally connected the upper end of the inner leg 22 of a strap, the outer leg 23 of which projects upwardly outside the cylinder 20.
- The upper end of the outer leg 23 of this strap is suitably connected to the lower edge of the window frame or sliding panel 12 and the substantially parallel legs 22 and 23 function as a piston rod connection between piston 21 and the sliding panel.
- Leg 22 is arranged for sliding movement on the face of a channel bar 24 having its lower end pivotally connected to the bottom of the door 10 and which bar projects upwardly and terminates within the lower end of cylinder 20.
- The upper end of bar 24 is bent to form an inverted L-shaped member 25, the vertical leg of which is loosely supported by a pin or stud 26 that is seated in the wall of cylinder 20 (see Figs. 5 and 6).
- Secured by a rivet 27 or other suitable means to the upper portion of bar 24, just below the inverted L-shaped member 25, is a depending lip or extension that is formed integral with the lower portion of a horizontally disposed open ended loop 28, the outer wall of which overlies the outer face of inner leg 22 of the piston rod member.
- Suitably secured to the bar 24 and within the loop 28 is a bow spring 29, the free ends of which bear against the inner wall of loop 28. This loop functions as a clutch or brake to engage the leg 22 and clamp the same against bar 24 to hold the window or panel in open, closed or intermediate positions.
- Suitably secured, preferably by means of a stud 30, to the bar 24 below loop 28, is the inner wall of a double-walled disc-shaped diaphragm 31 and carried by the inner wall of this diaphragm is a grooved stud 32, that is engaged by 35 the bifurcated lower end of a lever 33. This lever extends upwardly between the inner wall of loop 28 and the depending leg of the L-shaped member 25 and the upper end of said lever is fulcrumed to the upper portion of said inverted 40 L-shaped member.
- Located at any convenient point on the vehicle, preferably beneath the engine hood or below the floor of the car body, is a vacuum tank 34 and leading from one end thereof to 45 the intake manifold of the internal combustion engine that furnishes motive power for the vehicle, is a tube 35. Located in this tube is a check valve comprising a housing 36, within which is disposed a flexible diaphragm 37, preferably of metal, and formed in the center of said diaphragm is a relatively small port 38.
- 50 This form of check valve is designed to provide a fluid tight joint between the diaphragm and the plug 39 so that a substantial and sufficient degree of vacuum may be maintained within tank 34 for a considerable period of time in order that the window raising and lowering apparatus may function in the desired manner without depending on the suction produced within the intake manifold of the engine. Thus the apparatus may be operated while the engine is stopped.
- 55 Located within the door, preferably to one side of the cylinder 20, is the valve that controls the operation of the window raising and lowering structure and said valve comprises a substantially circular housing 40 and an extension housing 41, the latter containing the master valve or valve that opens the conduit to the 60 vacuum tank.
- 65 Formed in the extension housing 41 is a chamber 42, the lower end of which is closed by a removable cap 43 and leading from the vacuum tank 34, to this chamber 42, is a tube 44.

having a flexible portion 45 that is located so as to permit the door to swing upon its hinges.

5 A disc valve 46 is carried by a stem 47 and which valve normally closes a port 48 between the chamber 42 and the chamber within valve housing 40. An expansion spring 49 arranged beneath valve 46 normally holds the same against its seat.

10 Resting on the upper end of stem 47 is a hardened metal ball 50.

Arranged for rotation within valve housing 40 is a short cylindrical valve 51 having a large port 52 and a smaller port 53. Seated in the periphery of this valve 51 is a pair of hardened metal balls 54 that are adapted to engage ball 50 that bears on the stem of valve 46, such construction eliminating wear and reducing friction.

15 Formed through a lug or wall 55 that is formed at one end of port 52 and on the periphery of valve 51 is a port 56, which when valve 51 is in normal position as illustrated in Fig. 9 registers with a port 57 that is formed in the valve housing 40.

20 The peripheral wall of housing 40 is provided at its top with a port 58 and formed in said peripheral wall to the side of said port 58 is a port 59. Formed in the lower portion of the peripheral wall of the valve housing is a port 60.

25 Leading from port 58 to the upper end of cylinder 20 is a tube 61 and leading from port 59 to the lower portion of the cylinder is a tube 62.

30 Leading from port 60 downwardly through the door structure is a tube 63, that is connected to the inner ends of the tubes 16 that lead to the lower ends of the collapsible members 14 and leading from said tube 63 to a port in stud 30 that communicates with the interior of the diaphragm 31 is a tube 64.

35 Valve 51 is provided with an axial stem 65 that projects through the rear wall of the valve housing 40 and suitably secured to said stem immediately adjacent to the rear wall of the housing is a disc 66 having oppositely discharged slots or notches 67 formed in its edge.

40 Positioned immediately against the face of disc 66 and passing around the stem 65 are oppositely arranged springs 68, the ends of which overlie each other and said overlying ends being slightly spaced apart.

45 Passing between the spaced ends of these springs and seated in the disc 66, adjacent to the centers of the slots 67, are pins 69 and similar pins 70 are seated in the wall of the housing and project between the spaced ends of the springs (see Fig. 8).

50 This arrangement of springs and pins is provided in order to normally hold the valve 51 in its neutral position as illustrated in Fig. 9 and to automatically return said valve to neutral position after having been shifted in either direction.

55 Springs 68 are retained in position on stem 65 by means of a washer 71.

60 A stem 72 projects axially from the front side of valve 51 and carried by said stem is a handle 72 that normally occupies a vertical position as illustrated in Figs. 1 and 9.

65 Under normal conditions the valve structure that controls the operation of the window raising and lowering device occupies the position as illustrated in Fig. 9 with ports 57 and 58 closed and with master valve 46 closed and with ports

59 and 60 open. Under such conditions the collapsible members 14 at the sides of the window or panel are expanded so as to press the runners 18 against the edges of the window frame or panel and firmly hold same in its adjusted position.

70 Diaphragm valve 31 is in its normal expanded position so that the lower end of lever 33 is held at its outer limit of movement so that loop 28 is relieved of pressure by the upper portion 10 of said lever and spring 29 exerts pressure on the inner wall of said loop so as to cause the outer wall thereof to exert clamping pressure against leg 22, thereby holding the same against vertical movement. Consequently the window frame or panel is held firmly in either open, 15 closed or intermediate position.

75 With the parts so positioned, the suction produced in the intake manifold of the engine while running, will flex diaphragm 37 so as to draw 20 the same away from the plug 39 and thereby producing a partial vacuum within tank 34 and this tank is of such size as to retain this vacuum for a considerable period of time when the engine is stopped.

80 To lower the window frame or sliding panel, handle 72 is swung a short distance approximately 15° toward the lefthand and one of the balls 54 will engage ball 50 to force stem 47 carrying the master valve 46 away from port 30 48 and at the same time establishing communication between ports 58 and 59 through port 53 in the valve and closing port 57. Under such conditions the two valves within the housings 40 and 41 occupy the positions as illustrated in 35 Fig. 10.

85 Thus the chamber within cylinder 20 above the piston is open to the atmosphere through line 61, ports 58, 53 and 59 and line 62 that leads to the open lower end of the cylinder 40 and partial vacuum that prevails within tank 34 will be established in the collapsible members 14 and the double walled diaphragm 31 through line 44, the chamber within valve housing 41, ports 52 and 60, line 63, branch lines 45 16 and line 64.

90 The suction produced by the partial vacuum established in members 14 will collapse the same so as to relieve pressure of the runners on the side edges of the window frame or panel and diaphragm 31 will be collapsed so as to draw the lower end of lever 33 inwardly.

95 The upper end of said lever, which is fulcrumed on the inverted L-shaped member 25, will press loop 28 outwardly against the resistance offered by spring 29, thereby moving the outer wall of said loop away from leg 22, so as to permit same to move freely downward and which movement is produced by the window frame or panel which slides downward under 100 its own weight.

Thus the window or panel may be permitted to lower to its limit of movement or to any intermediate position and upon release of the handle 72, the parts of the valve will return 105 to their normal positions with master valve 46 closed, with the result that the vacuum within the collapsible members 14 and diaphragm 31 being cut off will permit said members and diaphragm to expand to exert pressure on the 110 edges of the panel and to permit the brake or clutch comprising the loop 28 and spring 29 to return to their normal positions to clamp leg 22 against bar 24.

115 If lever 72 is manipulated so as to hold the 75

valves open for a sufficient period of time to permit the window frame or panel to move downward to its limit of movement, the sudden descent of said frame or panel will be arrested and cushioned as it approaches the lower end of its travel as a result of the piston 21 closing the end of line 62 as said piston approaches the lower end of the cylinder.

When the end of the line 62 is closed by the piston, suction will be produced in the chamber within the upper portion of the cylinder through lines 61 and 62 and ports 58, 59 and 59, and this suction acting upon the piston will arrest and cushion its downward movement so as to prevent sudden jar of the window frame or panel at the lower end of its travel.

To elevate the window frame or panel, lever 12 is shifted for a short distance approximately fifteen degrees toward the righthand as illustrated in Fig. 11 and coincident with this movement one of the balls 54 will engage ball 50 to unseat master valve 46 and port 57 will be closed and at the same time communication between ports 58 and 60 will be established through port 52.

The partial vacuum prevailing in tank 34 will now exert suction through line 44, master valve chamber 42, ports 60, 52 and 58 and through line 61 to the chamber in the cylinder above piston 21, and this suction will likewise be produced in the collapsible members 14 and double-walled diaphragm 31 through line 63, branch line 16 and line 64.

As a result of this partial vacuum produced in members 14, the same will be partially collapsed to relieve the pressure on the side edges of the sliding panel and the collapse of the double-walled diaphragm 31 will actuate lever 33 so as to press loop 28 outwardly to relieve pressure upon leg 22, thus permitting the window frame or panel to move upwardly as a result of the suction produced in the chamber of cylinder 20 acting upon the piston 21 in said cylinder.

Inasmuch as piston 21 is connected to the lower end of the sliding panel by the piston rod member comprising the legs 22 and 23, said panel will be elevated as the piston is drawn upward by the partial vacuum prevailing in the cylinder above said piston.

Upon release of the handle 12, the master valve 46 and valve 51 will return to their normal positions as illustrated in Fig. 9, whereupon the members 14 will expand to exert pressure on the side edges of the window frame or panel and the brake comprising loop 28 and spring 29 will return to its normal position to clamp leg 21 against bar 24 and thereby firmly hold the panel in its elevated position.

The cooperating springs 68 and pins 69 and 70 provide means for yieldingly resisting the movement of lever 12 in both directions and for immediately returning said lever to its normal neutral position after said lever has been moved in either direction and then released.

Among the particularly desirable and advantageous features of my invention are the provisions of a vacuum storage tank which enables the window raising and lowering means to function repeatedly even though the engine is not running, further the collapsible members which normally exert pressure on the side edges of the sliding window frame or panel to firmly hold the same at any desired point in its travel and which members are collapsed to relieve the panel

of pressure when the same is raised or lowered, further, the brake or clutch that engages the piston rod member between the piston and sliding panel for engaging and holding said member against movement in either direction until said brake or clutch is released, the check valve that is located in the line between the intake manifold of the engine and the vacuum storage tank the convenient and space economizing arrangement whereby practically all of the operating parts of the structure are arranged within the door below the opening for the sliding window frame or panel.

A further advantageous feature of my improved construction is the use of an elliptical cylinder and the construction and combination of the various parts of the device whereby the same may be conveniently installed in the curved or convex doors that are now generally employed in automobile bodies.

Thus it will be seen that I have provided an automobile window operating means that is relatively simple in construction, inexpensive of manufacture and installation and very effective in performing the functions for which it is intended.

It will be understood that minor changes in the size, form, and construction of the various parts of my improved automobile window operating means may be made and substituted for those herein shown and described without departing from the spirit of the invention, the scope of which is set forth in the appended claims.

I claim as my invention:

1. The combination with a frame provided with an opening and a panel arranged for sliding movement in said frame and adapted to close said opening, of a cylinder arranged within said frame below the opening therein, a piston arranged for operation within said cylinder, a substantially U-shaped member providing a connection between said piston and said panel, a guiding support for said U-shaped member, a brake for normally engaging said U-shaped member and holding same against movement, vacuum operated means for effecting a release of said brake, and means for simultaneously producing vacuum in the cylinder above said piston and within said vacuum operated brake releasing means.

2. In an automobile window operating device, the combination with a frame provided with an opening and a panel arranged for sliding movement in said frame for closing said opening, of a cylinder arranged within the frame below the opening therein, a piston arranged for operation within said cylinder, a substantially U-shaped piston rod member connecting said piston with the lower portion of said sliding panel, a guiding support for said piston rod member, a brake for normally engaging said piston rod member to hold the same against movement, vacuum actuated means for effecting a release of said brake, collapsible members for normally exerting pressure on the side edges of the sliding panel, and means for simultaneously producing vacuum in the cylinder above said piston, within said brake releasing means, and within said collapsible members.

3. In an automobile window operating device, a frame provided with an opening, a panel arranged for sliding movement in said frame and adapted to close the opening therein, a cylinder arranged within the frame below the

opening therein, a piston arranged for operation within said cylinder, a substantially U-shaped member having the upper end of one of its legs connected to said piston, the upper end of the other leg being connected to the lower portion of the sliding panel, and means for producing a vacuum within the cylinder above the piston therein.

4. An automobile window operating device as set forth in claim 3, a brake for engaging one of the legs of said U-shaped member, and vacuum actuated means for releasing said brake.

5. An automobile window operating device as set forth in claim 3, a brake for engaging one of the legs of said U-shaped member, vacuum actuated means for effecting a release of said brake, and means for simultaneously producing vacuum within the cylinder above said piston and within said vacuum actuated brake releasing means.

6. In an automobile window operating device, a frame provided with an opening, a panel arranged for sliding movement in said frame and adapted to close the opening therein, a cylinder arranged within the frame below the opening therein, a piston arranged for operation within said cylinder, a member connecting said piston with the lower portion of said sliding panel, means whereby vacuum is produced in the cylinder above said piston to elevate the latter, and means whereby the downward movement of the piston within the cylinder as it approaches its downward limit of movement produces a partial vacuum within the cylinder above the piston so as to arrest and cushion the movement of said piston during the final portion of its downward travel in said cylinder.

7. In an automobile window operating device, a frame provided with an opening, a panel arranged for sliding movement in said frame for closing the opening therein, a cylinder arranged within said frame, a piston arranged for operation within said cylinder, a substantially U-shaped member having the upper end of one of its legs connected to said piston, the upper end of the other leg being connected to the lower portion of the sliding panel, a guiding member arranged in the lower portion of the frame and engaging one of the legs of said U-shaped member, and a vacuum actuated brake for clamping the leg of said U-shaped member to said guiding member.

8. In an automobile window operating device, a frame provided with an opening, a panel arranged for sliding movement in said frame and adapted to close the opening therein, collapsible means for normally exerting pressure on the side edges of the sliding panel, a cylinder arranged within said frame, a piston arranged for operation within said cylinder, a member connecting said piston with the lower portion of said sliding panel, a fixed guide for said connecting member, a brake for engaging said connecting member to hold the same against movement, vacuum actuated means for releasing said brake, a vacuum tank, a valve, a duct leading

from said vacuum tank to said valve, ducts leading from said valve to said collapsible means, ducts leading from said valve to the upper and lower portions of said cylinder, and a duct leading from said valve to said vacuum actuated brake releasing means.

9. In an automobile window operating device, a frame having an opening, a panel arranged for sliding movement in said frame for closing the opening therein, a cylinder arranged within the frame below the opening therein, a piston arranged for operation within said cylinder, a substantially U-shaped member having one leg connected to said piston and the other leg to the lower portion of said sliding panel, a guide for one of the legs of said U-shaped member, a brake mounted on said guide, which brake normally engages the leg of the U-shaped member that bears on said guide, vacuum actuated means for effecting a release of said brake, and means for producing a partial vacuum in said cylinder, above the piston therein.

10. An automobile window operating device as set forth in claim 9, with collapsible members normally engaging the side edges of said sliding panel, and means for producing vacuum in said collapsible means simultaneously with the operation of the vacuum actuated panel elevating means and the vacuum actuated braking releasing means.

11. In an automobile window operating device, the combination with a frame provided with an opening, the upright side members of which frame are provided with channels, of a panel arranged for sliding movement in said frame with its side edges occupying said channels, collapsible members located in said channels on opposite sides of the edges of said panel, narrow channels arranged between the side faces of the panel and said collapsible members, cushions carried by said narrow channels and engaging the side faces of said panel and cushions arranged between the side edges of said panel and the inner walls of the channels on said upright side members of the frame.

12. In an automobile window operating device, the combination with a frame provided with an opening, the upright side members of which frame are provided with channels, of a panel arranged for sliding movement in said frame and adapted to close the opening therein, collapsible members arranged within said channels, narrow channel members arranged in said channels between said collapsible members and the side faces of said panel, cushions carried by said narrow channel members and engaging the side faces of said panel, cushions arranged between the vertical edges of the panel and the inner walls of the channels on the upright side members of the frame and means for expanding said collapsible members to exert pressure on the narrow channels and the cushions carried thereby.
